CLAIM

The ornamental design for a wig base cap as shown and described.

DESCRIPTION

FIG. 1 is a front view of a wig base cap showing my new design;

FIG. 2 is a rear view of the wig base cap;

FIG. 3 is a right side view of the wig base cap;

FIG. 4 is a left side view of the wig base cap;

FIG. 5 is a top view of the wig base cap;

FIG. 6 is a bottom view of the wig base cap; and,

FIG. 7 is a top front side perspective view of the wig base cap in an alternate use position.

The broken lines in FIG. 7 are illustrative of environmental structure forming no part of the claimed design.
